UNITED STATES PATENT OFFICE

JOHN F. FETTERLY, OF ORANGE, NEW JERSEY, ASSIGNOR TO THE DRAPER MANUFACTURING COMPANY, OF CLEVELAND, OHIO, A CORPORATION OF OHIO

CONTAINER AND SEALING MEANS THEREFOR

Application filed May 17, 1930. Serial No. 453,236.

The invention relates to containers such as metallic barrels, drums and the like, utilized for containing industrial alcohol, oil, grease, and the like, which containers are formed 5 with bung openings providing means for entering or withdrawing fluid material into or from the container.

Plug means are commonly provided for the bung openings of such containers, which 10 are commonly sealed by the usual wire and lead seal construction known in all the arts. Such wire and lead seal sealing means are so common that many persons have access to the same, and it has been found that barrels 15 or drums containing alcohol, oil, grease and the like frequently have their bung opening seal broken, and the contents partly or entirely drained off; the container may then be refilled by the thief with water or other material 20 whereupon a new wire and lead seal is provided for the bung opening plug. Such theft of contents does not become apparent for some while after the theft has occurred 25 because there is no visible sign of the theft having taken place.

It has therefore been proposed that a non-refillable container be provided which includes means for preventing undetectable access to, and removal of, such plugs. Certain 30 constructions have been suggested for guarding against undetected opening of or removal of the plugs by providing a supplemental cover for the plug which entirely encloses the plug and which must be removed 35 so as to give a visible sign of removal, before the plug can be removed.

Other means have been suggested including the provision of a plug with a usual tumbler key lock which ordinarily seals the container 40 against theft but which does not give a visible or detectable sign of theft if the lock is picked.

Other means have been suggested for preventing theft which includes providing 45 means on the plug for mutilating or destroying the bung or bung threads upon removal of the plug so that the plug cannot then again be inserted, thus providing a visible or detectable sign that the container has been 50 opened.

All of these prior constructions are impractical from a commercial standpoint because they damage the container so as to prevent subsequent use thereof, or they have a prohibitive cost of manufacture, or their character is such that a liquid seal between the plug and bung opening cannot be properly effected.

One of the objects of the present invention is therefore to provide a container bung opening and plug construction in which the plug is automatically locked to the container upon being assembled therewith. Another object of the present invention is to provide theft sealing means for the plug which must 60 be mutilated or destroyed before the contents of the container may be drawn off through the bung opening, or before the plug 65 can be removed.

The provision of such a construction results in a container which is substantially 70 non-refillable, and it is therefore a further object of the present invention to provide means for releasing the plug from its locked relation with the bung ring after the theft 75 sealing means has been mutilated or destroyed so that a new theft sealed plug may be inserted into the bung opening in order that the container may again be used by authorized persons, thus giving a salvage 80 value to the non-refillable theft proof container.

These and other objects may be obtained by providing a construction, preferred embodiments of which are hereinafter set forth 85 in detail, which may be stated in general terms as including a container having a bung opening formed in one wall thereof, plug means for the bung opening, means automatically locking the plug to the bung opening 90 upon assembling the plug in sealing relation with the bung opening, destructible means carried by the plug enclosing the automatic means, for preventing access to the automatic 95 means without destruction of the destructible means, the automatic means being so constructed as to permit withdrawal of the plug upon destruction of the destructible means.

Preferred embodiments of the invention are 100

shown in the drawings, forming part of the specification in which—

5 Figure 1 is a section through a container wall having a bung opening closed by one form of the improved theft sealed plug;

Fig. 2 is a section similar to Fig. 1 showing the plug of Fig. 1 being assembled in the bung ring of the bung opening;

10 Fig. 3 is a plan view of the improved plug shown in Fig. 1;

Fig. 4 is a side elevation of the plug shown in Fig. 1 detached from the container;

Fig. 5 is a section through the improved plug, taken on the line 5—5, Fig. 1;

15 Fig. 6 is a sectional view similar to Fig. 1 showing the theft seal broken and showing, diagrammatically, means for releasing the automatic plug lock;

Fig. 7 is a view similar to Fig. 1 showing a 20 modified form of construction;

Fig. 8 is a sectional view of the modified form of plug shown in Fig. 7 showing the same being threaded into the bung opening bushing ring;

25 Fig. 9 is a plan view of the modified form of plug shown in Fig. 7;

Fig. 10 is a sectional view through the modified form of plug shown in Fig. 7, taken on the line 10—10, Fig. 7;

30 Fig. 11 is a view similar to Fig. 1 showing a still further modification of the improved bung ring and plug construction;

Fig. 12 is a section of the modified form of 35 plug shown in Fig. 11, taken on the line 12—12, Fig. 11; and

Fig. 13 is a sectional view similar to Fig. 1 showing a still further modified form of the improved plug.

Similar numerals refer to similar parts 40 throughout the various figures in the drawings.

Referring first to the embodiment of the invention shown in Figs. 1 to 6 inclusive, the container, such as a barrel or drum, has one 45 wall 20 thereof formed with an opening 21 in which is received the interiorly threaded bung ring bushing 22 having a lower surface 23. The bushing 22 may be connected in liquid sealing relation with the wall 20 in any 50 suitable and well known manner.

An exteriorly threaded closure plug generally indicated at 24 may be screwed within the bushing 22 and is formed at its outer end with a preferably hexagonally shaped circumscripting flange 25 to receive a wrench for screwing or unscrewing. The flange 25 laps the bushing 22 and wall 20, and an annular sealing gasket 26 is preferably interposed between the flange 25 and bushing 22 so as to 55 provide a liquid or fluid tight seal therebetween.

The plug 24 is provided with an annular portion 27 depending below the threaded portion thereof and below the lower surface 23 60 of the bushing 22 when the plug is in assem-

bled relation with the bushing as shown in Fig. 1. Two preferably opposed lock openings 28 are provided in the annular portion 27 for receiving internal locking plungers 29 operable at the inner end of the plug and connected together by the spring member 30 for spring pressing the plungers 29 radially outwardly through the openings 28.

70 After the container is filled, the plug 24 is assembled in sealing relation with the bushing 22, the plungers 29 being depressed within the openings 28 so that the annular portion 27 may be inserted into the threaded opening of the bushing 22, whereupon the plug 24 may be screwed into the bushing 22, the plungers 28 riding along the bushing threads as shown in Fig. 2 of the drawings.

75 As the plug approaches the position in which the joint between the same and the bushing 22 will be sealed by the annular sealing ring 26, the plungers 29 will be automatically outwardly spring pressed to the position shown in Fig. 1, whereupon the plug may be screwed down tightly in sealing relation with the bushing 22 and sealing gasket 90 26. As shown in Fig. 1, the plungers 29 normally project outwardly from the plug 24 to a position where they will engage the under surface 23 of the bushing 22 to lock the plug to the container walls and to prevent 95 removal of the plug if any attempt is made to unscrew the plug.

99 The plug 24 is preferably generally tubularly shaped so as to include a through opening 31 for permitting access to the spring 100 pressed locking plungers 29. The through opening 31 is closed by a frangible theft proof disk closure partition member 32, which has its annular rim located or seated in a liquid tight manner in the annular recess 33 of the plug 24. Thus, the disk member 32 encloses the locking plungers 29 and normally prevents access to the same when the plug is assembled in the bung ring as shown in Fig. 1. However, upon mutilating 110 or destroying the disk member 32, access to the locking plungers may be had without damage to the plug per se, or to the bung ring.

115 In order to remove the plug 24, or in order to gain access to the contents of the container, the disk 32 must be mutilated or destroyed as shown at 32a in Fig. 6, whereupon a tool 34, indicated diagrammatically in dot-dash lines in Fig. 6, may be inserted through the opening 31 and engaged by its pins 34a and 34b with the spring 30 for retracting the plungers 29 to a position such as shown in Fig. 2 so that the plug 24 may be unscrewed and removed.

120 The above removal of the plug by an authorized person permits withdrawal of the contents of the container and a subsequent use of the container by refilling the same and by inserting a new plug 24 provided with un- 125

mutilated or undestroyed theft sealing means 32.

If it happens that some unauthorized person attempts to gain access to the contents of the container, the disk theft seal 32 must be mutilated as shown at 32a in order that the contents of the container may be drawn off, and such mutilation gives a visible or detectable sign of the fact that the contents 10 of the container has been tampered with and prevents refilling and closing of the container.

Of course it must be understood that if the unauthorized person has new plugs 40 in his or her possession, the container could be refilled following theft of contents without giving a visible signal that the contents of the container had been tampered with; but it is likewise understood that the tactics of unscrupulous persons who would provide themselves with a complete line of different sizes 20 of plugs cannot be coped with in any manner by any person.

Referring to the embodiment of the invention shown in Figs. 7 to 10, inclusive, the 25 container, such as a barrel or drum, has one wall 20 thereof provided with an opening 21 in which is received the interiorly threaded 21 in which is received the interiorly threaded bung ring bushing 22, having a lower surface 23, and the bushing 22 may be connected in 30 liquid sealing relation with the wall 20 in any suitable and well known manner.

An exteriorly threaded closure plug generally indicated at 40 may be screwed within the bushing 22 and is formed with a preferably hexagonally shaped circumscribing flange 41 to receive a wrench for screwing or unscrewing. The flange 41 laps the bushing 22 and wall 20, and an annular sealing gasket 26 is preferably interposed between the flange 40 and bushing 22 so as to provide a liquid or fluid tight seal therebetween.

The plug 40 is provided with an annular portion 42 depending below the threaded portion thereof and below the lower surface 23 45 of the bushing 22 when the plug is in assembled relation with the bushing as shown in Fig. 7.

The annular portion 42 is preferably provided with a peripheral groove 43 for receiving the discontinuous spring locking ring 44 which normally springs to the position shown in Figs. 7 and 10 of the drawings.

After the container is filled, the plug 40 is 55 assembled in connection within the bushing 22, the spring locking ring 44 being depressed with the annular groove 43 so that the annular portion 42 may be inserted in the threaded opening of the bushing 22, whereupon the plug 40 may be screwed into the 60 bushing 22, the spring ring riding along the bushing threads as shown in Fig. 8 of the drawings.

As the plug 40 approaches the position in 65 which the joint between the same and the bushing 22 will be sealed by the annular seal-

ing ring 26, the spring ring 44 will automatically spring outwardly to the position shown in Fig. 7 where the same will engage the under surface 23 of the bushing 22 to prevent removal of the plug if an attempt is 70 made to unscrew the plug. After the ring 44 has thus locked the plug against removal, the plug may then be screwed down tightly in sealing relation with the bushing 22 and sealing ring 26.

For permitting access to the contents of the container, the plug 40 is generally tubularly shaped so as to include a through opening 45. A destructible theft proof disk member 46 is provided for the through opening 45 80 and has its rim located in the recess 47 provided in the plug 40, so that the disk member 46 closes the opening 45 and prevents access to the container, except upon destruction of the disk.

In order to gain access to the contents of the container, the disk 46 must be mutilated or destroyed, whereupon the contents of the container may be drawn off, the mutilation of the disk 46 giving a visible sign of the fact that the contents of the container has 90 been tampered with, and preventing refilling and closing of the container.

Referring to the embodiment of the invention shown in Figs. 11 and 12, the container, such as a barrel or drum, has one wall 20 thereof provided with an opening 21 in which is received the interiorly threaded bung ring bushing 22a having a depending annular portion 50, and the bushing 22a may 100 be connected in liquid sealing relation with the wall 20 in any suitable and well known manner.

An exteriorly threaded closure plug generally indicated at 51 may be screwed within the bushing 22a and is formed with a preferably hexagonally shaped circumscribing flange 52 to receive a wrench for screwing and unscrewing. The flange 52 laps the bushing 22a, and an annular sealing gasket 26 is preferably interposed between the flange 52 and bushing 22a so as to provide a liquid or fluid tight seal therebetween.

The plug 51 is provided with an annular portion 53 depending below the threaded portion thereof and having a peripheral groove 54 formed therein.

Two preferably opposed lock openings 55 are provided in the depending portion 50 of the bushing 22a for receiving locking plungers 56 secured in any suitable manner to the leaf springs 57 which may be attached to the depending portion 50, at 58.

After the container is filled, the plug 51 is 125 assembled in connection with the bushing 22a by screwing the same downwardly therein, the lower bevelled edge 59 of the plug pressing the plungers 56 outwardly in their openings 55, so that when the plug approaches the position in which the joint be-

tween the plug and the bushing 22a will be sealed by the annular sealing gasket 26, the springs 57 automatically press the plungers radially inwardly to the position shown in Figs. 11 and 12 so that the plungers are engaged in the annular groove 54 of the plug to prevent removal of the plug if an attempt is made to unscrew the plug. The plug may then be screwed down tightly in sealing relation with the bushing 22a and sealing ring 26.

For permitting access to the contents of the container, the plug 51 is generally tubularly shaped so as to include a through opening 60. A destructible theft proof disk member 61 is provided for closing the through opening 60 and has its rim located in the recess 62 provided in the plug 51, so that the disk member 61 closes the opening 60 and prevents access to the container, except upon destruction of the disk.

In order to gain access to the contents of the container, the disk 61 must be mutilated or destroyed, whereupon the contents of the container may be drawn off, the mutilation of the disk 61 giving a visible sign of the fact that the contents of the container has been tampered with and preventing refilling and closing of the container.

Referring to the embodiment of the invention shown in Fig. 13, the container, such as a barrel or drum, has one wall 20 thereof provided with an opening 21, in which is received the interiorly threaded bung ring bushing 22b, provided with a depending annular portion 70, and the bushing 22b may be connected in liquid sealing relation with the wall 20 in any suitable and well known manner.

An exteriorly threaded closure plug generally indicated at 71 may be screwed within the bushing 22b and is formed with a preferably hexagonally shaped circumscribed flange 72 to receive a wrench for screwing or unscrewing. The flange 72 laps the bushing 22b, and an annular sealing gasket 26 is preferably interposed between the flange 72 and bushing 22b so as to provide a liquid or fluid tight seal therebetween.

The plug 71 is provided with an annular portion 73 depending below the threaded portion therof and having an annular groove 74 formed therein.

The depending portion 70 of the bushing 22b is preferably provided with a peripheral groove 75 for receiving the discontinuous spring locking ring 76 which normally springs to the position shown in Fig. 13 of the drawings.

After the container is filled, the plug 71 is assembled in sealing relation with the bushing 22b, the spring locking ring 76 being carried either in the groove 74 or 75 and is depressed in either of said grooves so that the annular portion 73 may be inserted in the

threaded opening of the bushing 22b, whereupon the plug 71 may be screwed into the bushing 22b.

As the plug approaches the position in which the joint between the same and the bushing 22b will be sealed by the annular sealing ring 26, the spring ring 76 will automatically spring to the position shown in Fig. 13 where the same will be engaged in both grooves 74 and 75 so as to prevent removal of the plug if an attempt is made to unscrew the plug. The plug may then be screwed down tightly in sealed relation with the bushing 22b and sealing ring 26.

For permitting access to the contents of the container, the plug 71 is generally tubularly shaped so as to include a through opening 77. A destructible theft proof disk member 78 is provided for the through opening 77 and has its rim located in the plug recess 79 in a liquid tight manner, so that the disk member 78 closes the opening 77 and prevents access to the container, except upon destruction of the disk.

In order to gain access to the contents of the container, the disk 78 must be mutilated or destroyed whereupon the contents of the container may be drawn off, the mutilation of the disk 78 giving a visible sign of the fact that the contents of the container has been tampered with, and preventing refilling and closing of the container.

Although the locking devices in the various modified forms of construction shown in Figs. 7 to 13 inclusive, are not as readily adapted for unlocking to permit withdrawal of the plug following mutilation or destruction of the theft seal disk, nevertheless the various locking members may be retracted so that the various plugs may be withdrawn.

Accordingly the theft proof sealing disks shown in Figs. 7 to 13, inclusive, effectively enclose the automatic locking means to prevent unlocking of the same excepting after a time when the sealing disks have been mutilated or destroyed.

In referring to the disks or partitions 32, 46, 61 and 78 herein as being "frangible", it is not intended to limit the same to be made of material which will merely shatter or splinter. The term "frangible partition" refers to a member made of material which may be readily or easily deformed, distorted, displaced or broken through without damaging the tubular plug member 24, 40, 51 or 71, for which the partition normally provides a closure, so as to provide for ready access to the plug member internal lock.

I claim:

1. In container closure construction including walls forming a bung opening, a tubular plug for the bung opening, internal locking means for locking the plug to the walls upon insertion of the plug in the opening, and a frangible closure partition mounted in the

- tubular plug enclosing the locking means, whereby the partition normally forms a closure for the plug and whereby deformation of the partition permits access to the locking means without damage to the plug. 5
2. In container closure construction including walls forming a bung opening, a tubular plug for the bung opening, internal locking means for automatically locking the plug to the walls upon insertion of the plug in the opening, and a frangible closure partition mounted in the tubular plug enclosing the locking means, whereby the partition normally forms a closure for the plug and whereby deformation of the partition permits access to the locking means without damage to the plug. 10
3. In container closure construction including walls forming a bung opening, a tubular plug for the bung opening having an internal lock for automatically locking the plug to the walls upon insertion of the plug in the opening, and a frangible closure partition mounted in the tubular plug enclosing the lock, whereby the partition normally forms a closure for the plug and whereby deformation of the partition permits access to the lock without damage to the plug. 15
4. In container closure construction including walls forming a bung opening, a tubular plug for the bung opening, spring locking means for automatically locking the plug to the walls upon insertion of the plug in the opening, and a frangible closure partition mounted in the tubular plug enclosing the locking means rendering the same inaccessible when the plug is locked to the container walls, whereby the partition normally forms a closure for the plug and whereby deformation 20 of the partition permits access to the locking means without damage to the plug. 25
5. In container closure construction including a bung ring, a tubular plug for the bung ring, locking means automatically positioned to cooperate with the plug and ring to lock the plug in the ring upon insertion of the plug in the ring, and a frangible closure partition mounted in the tubular plug enclosing the locking means rendering the same inaccessible when the plug is locked in the ring, whereby the partition normally forms a closure for the plug and whereby deformation 30 of the partition permits access to the locking means without damage to the plug. 35
6. In container closure construction, a bung ring, a tubular plug for the bung ring, locking means carried by the plug automatically positioned to cooperate with the plug and ring to lock the plug in the ring upon insertion of the plug in the ring, and a frangible closure partition mounted in the tubular plug enclosing the locking means rendering the same inaccessible when the plug is locked in the ring, whereby the partition normally forms a closure for the plug and whereby de- 40
- formation of the partition permits access to the locking means without damage to the plug. 45
7. In container closure construction, a bung ring, a tubular plug for the bung ring, locking means carried by the bung ring automatically positioned to cooperate with the plug and ring to lock the plug in the ring upon insertion of the plug in the ring, and a frangible closure partition mounted in the tubular plug enclosing the locking means rendering the same inaccessible when the plug is locked in the ring, whereby the partition normally forms a closure for the plug and whereby deformation of the partition permits access to the locking means without damage to the plug. 50
8. In container closure construction including walls forming a bung opening, a tubular plug for the bung opening, internal locking means for locking the plug to the walls upon insertion of the plug in the opening, there being an annular recess in the tubular plug, an a frangible closure partition seated in the recess of the tubular plug enclosing the locking means, whereby the partition normally forms a closure for the plug and whereby deformation of the partition permits access to the locking means without damage to the plug. 55
9. In container closure construction including walls forming a bung opening, a tubular plug for the bung opening having an inner and outer end, releasable internal locking means operable at the inner end of the plug for locking the plug to the walls upon insertion of the plug in the opening, and a frangible closure partition mounted in the tubular plug interposed between said releasable means and the outer end of the plug enclosing the locking means, whereby the partition normally forms a closure for the plug, whereby deformation of the partition permits access to the locking means without damage to the plug and whereby the locking means may be released upon deformation of the partition. 60
- In testimony that I claim the above, I have hereunto subscribed my name.
